UNITED STATES PATENT OFFICE.

BERNHARD HEUMANN, OF ROCHESTER, AND FRANKLIN B. PEASE, OF
ONTARIO CENTRE, NEW YORK.

CLOTH MEASURING AND FACING MACHINE.

SPECIFICATION forming part of Letters Patent No. 310,425, dated January 6, 1885.

Application filed May 7, 1884. (No model.)

To all whom it may concern:

Be it known that we, BERNHARD HEUMANN and FRANKLIN B. PEASE, citizens of the United States, residing, respectively, at Rochester 5 and Ontario Centre, in the counties of Monroe and Wayne and State of New York, have invented certain new and useful Improvements in Cloth-Measuring Machines; and we do declare the following to be a full, clear, and exact 10 description of the invention, such as will enable others skilled in the art to which it appertains to make and use the same, reference being had to the accompanying drawings, and to the letters and figures of reference marked 15 thereon, which form a part of this specification.

This invention relates to improvements in cloth measuring and facing machines; and it consists in the construction and arrangement 20 of parts, as hereinafter more fully described and claimed.

In the annexed drawings, illustrating the invention, Figure 1 is a perspective view of our improved cloth measuring and facing machine. Fig. 2 is a vertical sectional view of the same arranged in connection with a table. Fig. 3 is a top view of the machine, showing the upper frame and roller partly turned.

The main frame of the machine consists of 30 the standards A A and cross-piece B. Near the lower ends of the standards is journaled a removable roller, C, and upon the top of the cross-piece B is pivoted a frame, D, in which is journaled a roller, E, having a crank, F, at 35 one end.

At the front of the machine, and attached to one of the standards, is a bracket, G, in which is journaled a measuring-roll, H, having a shaft, I, that is connected to a registering mechanism, K, of any suitable construction. This registering mechanism is contained 40 in a case at one end of the bracket G, as shown in Fig. 1. The roll H is mounted on one end of its shaft I and occupies a position about 45 half-way between the standards A A and rollers C E.

At the back of the measuring-roll H is a yielding pressure-foot, L, that is held by means of a spring, M, in close contact with the cloth 50 that is passed between it and said roll.

To the standards A A, on each side of the

pressure-foot L, are attached guides N N, that assist in preventing the cloth from wrinkling or lapping as it is passed between the pressure-foot and the measuring-roll H, a sufficient space between the pressure-foot and guides being afforded for the free passage of the cloth in starting the piece through, as an opportunity is thus afforded for taking hold of the piece of cloth with both hands near the center, thereby carrying it through easily. It can then be caught on small hooks that may be attached to the upper roller, E, or on hooks attached to webbing fastened on said roller; or the roller may be roughened or covered with some rough material that will hold the ends of the cloth by merely lapping it around the roller E; or any convenient means of connecting the end of the cloth to the roller E may be adopted, so as to prevent the cloth from slipping from said roller while being wound thereon, and at the same time hold it with the proper degree of tautness to insure an accurate measurement.

It is obvious that we may attach the spring 75 M either to the pressure-foot L or to the roller H, as desired.

The machine is intended for measuring cloth in manufacturing establishments and warehouses, and also for use by tailors and cutters 80 in carrying the cloth upon the cutting-table and facilitating its manipulation in the various processes of cutting.

In measuring cloth it is unrolled from the lower roller, C, carried upward between the measuring-roll H and pressure-foot L, and rolled onto the top roller, E, by turning the crank F. As the cloth passes between the pressure-foot L and measuring-roll H, the rotation of the latter actuates the registering 90 mechanism K through the shaft I and records the quantity. The opening or space on each side of the pressure-foot L and guides N N enables the cloth to pass with convenience and without liability of wrinkling or lapping. It 95 will be seen that the cloth is measured in the middle, where it passes between the roll H and pressure-foot L, the latter exerting a pressure or tension that causes the moving cloth to revolve the roll H, and so measure 100 and register with accuracy the quantity of material passed in contact with said roll. The

revolution of the roll H in its turn presses forward succeeding portions of the cloth against the curved surface of the pressure - foot smoothly and continuously and without allowing the slack cloth to make any lap in measuring. It will be understood, of course, that the circumference of the roll H equals some unit of length, or fractional part thereof, so that one complete revolution of the roll will 55 register a corresponding quantity. The pivoted upper roller, E, enables the cutter in tailoring establishments to handle the cloth with great facility and in much less time than is required when the work of folding and fac- 5 ing to bring the nap in the proper direction is done in the usual manner by hand alone. It will be seen that after the whole roll of cloth is rolled from the lower roller, C, to the upper roller, E, and thus measured, the cutter knows exactly how many yards there are in the piece. He then makes his calculations as to how many pieces of a certain length he can cut from said roll of cloth. He then draws from said roll onto the cutting-table one piece of the required length, measuring this length by hand, and cuts it off. Then he reverses the roll of goods by giving the pivoted frame D a half-turn, draws another length, and cuts it off, which 30 faces the cloth on the table and brings the nap of the goods right for the cutting, and so on until he has as many thicknesses as he desires to cut. He is then ready for cutting without going through the present tiresome and tedious process of folding and turning the goods by hand. By means of the swinging roller E each of several pieces of cloth can thus be 35 readily faced, without the great amount of folding and handling usually required, so as to bring the nap alike in all. It is obvious that 40 the roller E and its frame D can either be mounted upon the cross-piece B, as shown, or suspended in any suitable manner from the top of the machine, as desired. The manner of placing the machine with relation to the table

is shown in Fig. 2; and it will be observed that 45 while the cloth is being passed through the machine the dust and other substances often found in cloth will fall to the floor without reaching the surface of the table.

Instead of placing the roll of cloth in the 50 machine upon a lower roller, C, as shown, said roll of cloth may be laid in a suitable box placed at the base of the standards; or the same result will be accomplished by passing a small rod through the center of a roll of 55 cloth and hanging it in place of the roller C.

Having thus described our invention, what we claim as new, and desire to secure by Letters Patent, is—

1. In a cloth-measuring machine, the combination of the measuring-roll H, mounted on the shaft I, a registering mechanism, K, connected to said shaft, the pressure-foot L, spring M, and guides N N, substantially as described. 60

2. In a cloth-measuring machine, the combination of the rollers C E, measuring-roll H, mounted on the shaft I, a registering mechanism, K, connected to said shaft, the yielding pressure-foot L, and the guides N N, substantially as described. 65

3. A cloth measuring and facing machine consisting of the frame A B, having guides N N and bracket G, a registering mechanism, K, carried by said bracket, a measuring-roll, H, mounted on a shaft, I, journaled in the 70 bracket and connected to said registering mechanism, the pressure-foot L, and spring M, attached to the cross-piece B, the lower roller, C, and the pivoted frame D, carrying roller E, substantially as described. 75

In testimony whereof we affix our signatures in presence of two witnesses.

BERNHARD HEUMANN.
FRANKLIN B. PEASE.
